UNITED STATES PATENT OFFICE

KENNETH PERKINS, OF ELIZABETH, NEW JERSEY, ASSIGNOR TO THE SINGER MANUFACTURING COMPANY, OF ELIZABETH, NEW JERSEY, A CORPORATION OF NEW JERSEY

ELECTRIC LAMP SOCKET

Application filed June 16, 1928. Serial No. 285,801.

This invention relates to electric lamp-sockets and has for an object to provide a lamp-socket the casing of which tightly encloses the socket-switch mechanism so as to protect the latter from dust or other extraneous matter which may interfere with its proper working. A further object of the invention is to provide a lamp-socket having switch-mechanism and a switch-operating button which is directly supported by the socket-shell, rather than by the socket-insides, and is thus stronger and more resistant to damage.

To the attainment of the ends in view, the socket-shell preferably comprises body and detachable cap sections molded from a phenolic condensation product or other suitable molding material having the requisite strength and resistance to heat. The switch-operating button is directly and slidably mounted on the socket-shell, preferably by forming the shell with a longitudinally extending slot or slideway and by grooving or undercutting the sides of the button to fit the slideway; the button having outer and inner flanges overlapping the outer and inner walls of the socket-shell adjacent the slot in the latter, so that the button can only be removed by removing the cap-member and shifting the button out of the slideway. The button is formed with apron extensions which alternately close each end of the slideway when the button is shifted back-and-forth. The switch-mechanism is preferably of the toggle-operated type including a lever which freely projects into a socket in the under side of the slidably mounted operating button.

In the accompanying drawings, Fig. 1 is a longitudinal section of an electric lamp-socket embodying the invention. Fig. 2 is a section on the line 2—2, Fig. 1, showing the operating button in end elevation. Fig. 3 is a section on the line 3—3, Fig. 1. Figs. 4 and 5 are, respectively, side and end elevations of the operating button, and Fig. 6 is a disassembled perspective view of the socket-shell.

The invention is preferably embodied in a socket having a body or shell 1 reduced at

one end to form the usual lamp-base receiving aperture 2 and having at its other end a thickened rim 3. The body 1 is also formed with a longitudinally extending slot 4 in which is slidably mounted the base of the switch-operating button 5. The sides of the base of the button 5 are grooved at 6 to form outer and inner flanges 7, 8, which engage the outer and inner surfaces of the shell 1 adjacent the slot 4.

The large end of the shell 1 is closed by the cap 9 which is secured to the shell by screws 10. The cap 9 is also preferably of molded construction with a metal insert sleeve 11 and reinforcing ring 12 having a slot in it at 13 through which the molding material flows to connect the filler-block 14 for the open end of the slot 4 with the body of molding material beneath the metal ring 12. The filler-block 14, entering the slot 4, also serves to register the holes in the cap and shell for the screws 10. The button 5 is formed at its opposite ends with apron extensions 15 which alternately close the opposite ends of the slot 4 when the button is slid back-and-forth. The button 5 is also formed in its under side with a slot 16 to receive the end 17 of the operating lever 18 for the socket-switch 19.

The socket-switch 19 is preferably of the toggle-type constructed substantially in accordance with the disclosure of the patent to D. H. Chason, No. 1,641,134 of August 30, 1927. In such a switch mechanism there is fulcrumed on the pin 20, which supports the lever 18, a carrier frame 21 for a bridging contact member 22 which at one extreme of its throw bridges the contacts 23, 24. There is pivoted to the lever 18 at 25 one end of a toggle-member 26, the other end of which is slidably received in a slot in the frame 21. An expansion spring 27 surrounds the toggle-member 26.

There is screwed onto the end of the sleeve 11 a cord-inlet bushing 28, also of molded construction with a threaded metal sleeve insert 29 and notches 30, such bushing adapting the socket for use in the sewing machine lighting device disclosed in the patent to Chason No. 1,546,619 of July 21, 1925.

Having thus set forth the nature of the invention, what I claim herein is:

1. An electric lamp-socket comprising a socket-shell having a longitudinally extending slideway, a socket-switch mechanism received in said shell and having a pivoted switch-operating lever movable lengthwise of the socket-shell, and an operating button mounted in said slideway and supported by the socket-shell independently of the switch-mechanism and connected to said operating lever.
2. An electric lamp-socket comprising a socket-shell having a longitudinally extending slideway, a socket-switch mechanism received in said shell and having a pivoted switch-operating lever movable lengthwise of the socket-shell, and an operating button mounted in said slideway and supported by the socket-shell, said button being formed in its under side with a slot in which said operating lever freely extends.
3. An electric lamp-socket comprising a cylindrical socket-shell member having a slot extending from an open end of said member longitudinally of the latter, a second member detachably connected to said open end of the socket-shell member and closing the open end of said slot, a button having grooves in its sides slidably embracing the side edges of said slot and entirely supported and held in operative position by said socket-shell member, and a complete unitary socket-switch assembly enclosed by said socket-shell member and having a switch-operating element movable lengthwise of said slot and connected to said button.

In testimony whereof, I have signed my name to this specification.

40 KENNETH PERKINS.
